MAGAZINE TYPE RAZOR

George Douglas Jones, Los Angeles, Calif.

Application September 2, 1949, Serial No. 113,800

24 Claims. (Cl. 30—40)

1

This invention relates to safety razors and is particularly directed toward a novel form employing a double-edged ribbon blade of considerable length which may be unspooled from a magazine to present successive unused portions as desired.

The principal object of this invention is to provide a new and improved form of razor using a double-edged blade.

Another object is to provide a novel form of disposable blade magazine.

Another object is to provide a novel form of holder for containing a disposable magazine.

Another object is to provide a novel form of shaving razor using a double-edged blade and which is adapted for economical manufacture on a quantity basis.

A further object is to provide a shaving razor utilizing a double-edged ribbon blade and constructed in a manner so that the sharpened edges of the blade are kept out of contact with parts of the razor in order to maintain maximum sharpness.

Other and more detailed objects and advantages will appear hereinafter in connection with the drawings and the following description thereof.

In the drawings:

Figure 1 is a front elevation of a preferred embodiment of my invention.

Figure 2 is a plan view thereof, partly in section.

Figure 3 is a perspective view of a preferred form of holder and illustrating a preferred form of magazine in position for insertion into the holder.

Figure 4 is a sectional view taken on the line 4—4 of Figure 2.

Figure 5 is a sectional plan view taken on the line 5—5 of Figure 1.

Figure 6 is a front elevation of the blade magazine with cover removed, partly in section.

Figure 7 is a fragmentary section on an enlarged scale taken on the line 7—7 of Figure 4.

Figure 8 is a fragmentary section taken on the line 8—8 of Figure 4.

Figure 9 is a fragmentary section on an enlarged scale taken substantially on line 9—9 of Figure 4.

Figure 10 is a perspective view on an enlarged scale of a portion of the blade and showing one of the guide slots.

Figure 11 is a sectional view taken substantially on line 11—11 of Figure 6.

Referring now to the drawings, the holder,

generally designated at 10, is generally rectangular in shape and relatively thin compared to its length and width. The lower portion of the holder 10 may be curved to fit the hand, as shown in Figures 1 and 3. A magazine 11 is received into the pocket 12 defined by the sides and bottom of the holder 10, and this magazine carries a flexible ribbon blade 13 of considerable length. Both edges of the blade are sharpened as indicated at 14 and 15.

The magazine 11 is generally rectangular in shape and of such size as to form a snug fit when held in the holder 10. The lower edges of the magazine may be rounded as indicated in the drawings. The magazine may include a base 16 and a cover 17 secured by any means, such as, for example, by means of projecting pin elements 18 on the base 16 which extend through apertures 19 in the cover 17 and which are later deformed in the manner of a rivet to prevent disassembly. The cover 17 may comprise a metal stamping if desired and may be provided with a pair of annular ridges 17a to secure additional stiffness.

A horizontal slot 20 provided in the base 16 separates the main portion of the base 16 from the horizontal bridge 21. An opening 22 in the cover 17 is aligned with the base slot 20, and a pair of extending ears 23 and 24 overlie the bridge 21. The ribbon blade 13 extends across the upper surface 25 of the bridge 21 and under the ears 23 and 24. The ear 23 is upwardly curved as at 26 so that the edge of the blade will not be dulled by contact with the ear. The ears 23 and 24 serve to maintain the blade in position so that there is a minimum of bowing of the blade when the magazine 11 is not contained in the holder 10. The ribbon blade 13 extends from a supply coil 28 positioned within a recess 29 provided in the base 16. The other end of the blade 13 may be received in a mounting slot 30 provided in a take-up drum or reel 31 positioned within the recess 32. The recess 32 is also formed in the base 16 and is positioned symmetrically with the recess 29 with respect to the bridge 21.

A noncircular opening 33 is provided in the reel 31, and a cooperating noncircular projection 34 on the knob 35 is carried on the holder 10 and projects through an aperture 36 provided in the boss 37 on the holder 10. Friction lock 36a between aperture 36 and hub 38 is provided to maintain the projection 34 in engaged position in the noncircular opening 33. In order that the projection 34 may be disengaged from

the noncircular opening 33 so that the entry and withdrawal of the magazine 11 may be accomplished, a flange 39 is provided on the projection 34. As can be seen by the phantom lines in Figures 5, the projection 34 may be disengaged from the noncircular opening 33 by pulling out the knob 35, whereupon the flange 39 is retracted into the annular chamber 49 in the boss 37, and whereby disassembly is prevented. The cylindrical surface 41 of the knob may be roughened or serrated as shown.

The reel 31 is provided with outwardly extending hub portions 42 which are received within the axially aligned openings 43 and 44 provided in the base 16 and cover 17 respectively. Rotation of the knob 35 serves to wind the ribbon blade 13 onto the reel 31 and hence cause the blade to move across the bridge 21 and to unspool from the supply coil 28.

Rounded surfaces 45 and 46 are provided on the base 16 and are contacted by the ribbon blade 13 at each end of the bridge 21. Means are provided for protecting the edges of the blade 13 against contact with portions of the razor, and as shown in the drawings these means may include spindle 47, pin 48 carried on the spindle 47, and longitudinal slots 49 centrally located in the blade 13. The pin 48 engages in the slots 49 so that axial movement of the coiled ribbon blade is prevented. The slots 49 are of sufficient length that they may be engaged by the pin 48 when the blade 13 is in the coiled position as shown in Figures 5 and 6. Centering bosses 52 and 53 of the spindle 47 are journaled in apertures in the base 16 and cover 17, respectively. Correct alignment of the blade at the end adjacent the take-up reel 31 is maintained by means of groove 76 defined by shoulders 77 and 78 on the rounded surface 46. Only slight clearance between the edges of the blade and the shoulders 77 and 78 is provided. Either edge of the blade may come in contact with the shoulders, but this is not disadvantageous since the portion of the blade passing through the groove 76 has been used in shaving and it is no longer necessary that further dulling of the blade by contact with the razor be avoided. Tension is maintained on the blade 13 at all times as described below. By means of this tension, and the fact that the blade is unwound from the supply coil 28 in correct position and maintained in correct alignment by the groove 76, the desired position of the blade 13 is maintained so that the sharpened edges of the blade 13 do not come in contact with any portions of the razor until after use.

Means are provided to prevent unspooling of the reel 31 and thereby maintain tension on the ribbon blade 13. As shown in the drawings, this means includes a plurality of ratchet teeth 54 formed on the side face of the reel 31, together with a pawl element 55 for engaging the teeth 54. This pawl element 55 may be formed as an integral part of the cover 17 and may be separated by a stamping operation from the remainder of the cover along the radial line 56 and intersecting circumferential line 57. The pawl 55 is deformed inwardly as shown in Figure 9, and its integral connection with the cover 17 provides sufficient resilience to permit the pawl to deflect outwardly and allow the ratchet teeth 54 to pass by in one direction. Reverse rotation of the reel 31 is prevented. From this description it will be observed that a ratchet and pawl device has been provided for preventing a reverse rotation of the reel 31, which device requires no separate or additional parts and which may be manufac-

tured economically on a quantity basis. The tendency of the coil loops to expand within the recess 29, together with the friction of the blade 16 over the curved surface 45, provides sufficient frictional resistance to maintain proper tension on the blade as it reaches the bridge 21. The ratchet device prevents unwinding of the blade at the other end of the bridge.

The ribbon blade 13 extends from the supply coil 28 through a slot 58 leading from the recess 29 to the curved surface 45, the outer end of the slot being defined by the upper edge 59 of the end wall 60. A similar slot 61 is provided on the other side of the base 16 communicating with the recess 32. Nonmetallic sealing elements 62 and 63 may be provided adjacent the slots 58 and 61 in a position to contact the ribbon blade 13. These sealing elements 62 and 63 assist in excluding entrance of water or foreign matter into the recess 29 and 32.

Means are provided for maintaining the magazine 11 in position in the pocket 12 of holder 10 and at the same time to clamp the ribbon blade in position for shaving. As shown in the drawings, this means includes clamping bar 64 and spring 65. Clamping bar 64 is pivotally connected to holder 10 by means of pin 67 and bracket 68. The middle portion 69 of clamping bar 64 is of greater thickness than the remaining portions thereof so that the middle portion 69 of the bar may clamp down on the blade 13 without interference from the ears 23 and 24, as shown in Figures 1 and 4. The end portion 70 of the clamping bar 64 is outwardly bent so that it may be engaged in the depression 71 on the side of the holder 10, thus providing spring securing means for the clamping bar. Spring 65, secured to the holder by means of pins 72, is provided to force the magazine upwardly and against the clamping bar. The clamping bar 64, cooperating with bridge 25 and spring 65 exerts sufficient pressure on the blade 13, so that the blade is held sufficiently rigid for shaving. An aperture 73 may be provided in the bottom portion of the holder so that an object may be inserted therethrough to push the magazine 11 out of the holder when desired. The usual comb teeth 74 are provided along the upper edges of the holder.

The magazine 11 may be installed in the holder 10 merely by swinging the clamping bar 64 out of the way, pulling out the knob 35, and sliding the magazine 11 into the pocket 12. Recess 75 in the holder 10 affords clearance for the annular ridges 17a. The clamping bar is then swung into its secured position as shown in Figure 1, and the knob 35 is pushed inwardly to engage the projection 34 in the noncircular opening 33. The razor is then ready for use.

When the exposed or active portion of the sharpened edges 14 and 15 becomes dulled through use the knob 35 is rotated to bring a fresh portion into position on the bridge 21. A very large number of active lengths are thus provided on the relatively long ribbon 13. When the blade 13 has been completely exhausted, that is, wound on the reel 31, the clamping bar 64 is opened and the used magazine 11 withdrawn and discarded. A new magazine is then inserted into the pocket 12 as outlined above, and the device is again ready for use. The new magazine may be handled without using great care since the cutting edges 14 and 15 are well guarded and shielded against contact, except for the exposed or active length extending along the bridge 21. If desired, a portion of the blade 13 which is

initially exposed may have its cutting edges 14 and 15 dulled to further insure against accidental injury when installing the magazine 11 into the holder 10. When once installed, the knob 35 is turned to bring the sharpened portion of the blade into operative position. The last portion of blade which is exposed may likewise have its cutting edges dulled to insure against injury when the magazine is withdrawn from the holder.

Having fully described my invention, it is to be understood that I do not wish to be limited to the details herein set forth, but my invention is of the full scope of the appended claims.

I claim:

1. In a safety razor, the combination of: a holder; a disposable magazine member adapted to be removably contained in the holder, said magazine member having a recess for a ribbon blade coil; clamping means including a movable element adapted to secure the magazine member in operative position in the holder; and a spring member in said holder adapted to force the magazine against said movable element, thereby maintaining the magazine in operative position.

2. In a safety razor, the combination of: a holder; a disposable magazine member adapted to be removably contained in the holder, said magazine member having a recess for a ribbon blade coil and provided with a pair of spaced-apart blade-contacting ears; and clamping means on said holder including a movable element adapted to secure the magazine member in operative position in the holder, said element having a portion shaped to cooperate with said ears in contacting a ribbon blade.

3. In a double-edged safety razor, the combination of: a holder; a disposable magazine member adapted to be removably contained in the holder, said magazine member having a recess for a double-edged ribbon blade coil and provided with a pair of blade-contacting ears, said ears being spaced to present a two-sided shaving area therebetween; and clamping means including a movable element adapted to secure the magazine member in operative position in the holder.

4. In a double-edged safety razor, the combination of: a holder; a disposable magazine member adapted to be removably contained in the holder, said magazine member having a recess for a double-edged ribbon blade coil and provided with a pair of blade-contacting ears, said ears being spaced to present a two-sided shaving area therebetween; and clamping means including a movable element on the holder adapted to secure the magazine member in operative position in the holder with said ears adjacent said clamping means.

5. In a double-edged safety razor, the combination of: a holder; a disposable magazine member adapted to be removably contained in the holder, said magazine member having a recess for a double-edged ribbon blade coil and provided with a pair of blade-contacting ears, said ears being spaced to present a two-sided shaving area therebetween; and clamping means including a movable element adapted to secure the magazine member in operative position in the holder with said ears under said clamping means.

6. In a safety razor, the combination of: a holder; a disposable magazine member adapted to be removably contained in the holder, said member having a recess for a ribbon blade coil and provided with a pair of blade-contacting ears, said ears being spaced to present a two-

sided shaving area therebetween; and clamping means on said holder, said clamping means comprising a clamping bar pivotally connected to the holder and adapted to secure the magazine member in operative position in the holder with said ears under said clamping bar.

7. In a safety razor, the combination of: a holder; a disposable magazine member adapted to be removably contained in the holder, said member having a recess for a ribbon blade coil and provided with a pair of spaced-apart blade-contacting ears; and a clamping bar pivotally connected to said holder, the operative surface of said clamping bar being formed so as to cooperate with said ears in contacting a ribbon blade, while maintaining the magazine in operative position in the holder.

8. In a safety razor, the combination of: a holder; a disposable magazine member adapted to be removably contained in the holder, said member having a recess for a ribbon blade coil and provided with a pair of blade-contacting ears; a clamping bar pivotally connected to said holder, the operative surface of said clamping bar being formed so as to cooperate with said ears in contacting a ribbon blade; and a spring member in said holder adapted to force the magazine against said clamping bar, thereby maintaining the magazine in operative position.

9. In a double-edged safety razor, the combination of: a holder; a disposable magazine member adapted to be removably contained in the holder, said member having a recess for a double-edged slotted ribbon blade coil and provided with a spindle having a pin thereon for engagement in a slotted blade coil; and clamping means on said holder including a movable element adapted to secure the magazine member in operative position in the holder.

10. In a double-edged safety razor, the combination of: a holder; a disposable magazine member adapted to be removably contained in the holder, said member having a recess for a double-edged slotted ribbon blade coil and provided with a spindle having a pin thereon for engagement in a slotted blade coil; and clamping means on said holder, said clamping means comprising a clamping bar pivotally connected to the holder and adapted to secure the magazine in operative position in the holder with said ears in engagement under said clamping bar.

11. In a safety razor, the combination of: a holder; a disposable magazine member adapted to be removably contained in the holder, said member having a cavity for a double-edged slotted ribbon blade coil and provided with a spindle having a pin thereon for engagement in said slotted blade coil; a clamping bar pivotally connected to said holder, the operative surface of said clamping bar being formed so as to cooperate with said ears in contacting a ribbon blade; and a spring member in said holder adapted to force the magazine against said clamping bar, thereby maintaining the magazine in operative position.

12. In a double-edged safety razor, the combination of: a holder; a disposable magazine member adapted to be removably contained in the holder and provided with a pair of blade-contacting ears; a double-edged ribbon blade coil rotatably contained in a recess in said magazine member, said ribbon blade having a plurality of longitudinal slots centrally thereof; a spindle journaled in the recess in said magazine, said spindle having a pin thereon, said pin being engaged in said slots to restrict axial movement

of said coil; and clamping means on said holder including a movable element adapted to secure the magazine member in operative position in the holder.

13. In a double-edged safety razor, the combination of: a holder; a disposable magazine member adapted to be removably contained in the holder, said magazine member having a recess for a double-edged ribbon blade supply coil and a second recess to receive used portions of the blade; a winding reel journaled in said second recess; a winding knob rotatably mounted on the holder; a projection on the knob adapted to engage a recess in the reel whereby the latter may be turned; and means whereby the projection may be disengaged from the recess without disassembly.

14. In a double-edged safety razor, the combination of: a holder; a disposable magazine member adapted to be removably contained in the holder, said magazine member having a recess for a double-edged ribbon blade supply coil and a second recess to receive used portions of the blade; a winding reel journaled in said second recess; a winding knob rotatably mounted on the holder; a projection on the knob adapted to engage a recess in the reel whereby the latter may be turned; means whereby the projection may be disengaged from the recess without disassembly; and clamping means on said holder including a movable element adapted to secure the magazine member in operative position in the holder.

15. In a safety razor magazine, the combination of: a base member having a bridge thereon and having a first recess therein adapted to contain a double-edged ribbon blade supply coil and a second recess therein adapted to receive used portions of the blade; a winding reel journaled in said second recess, said winding reel having a noncircular recess axially thereof; means whereby a ribbon blade may be led from the first recess across the bridge and into the second recess; and a cover member for said base member, said cover member having a pair of ears transversely thereof adapted to overlie said bridge and to thus form narrow channels for a ribbon blade, said ears being spaced to present a two-sided shaving area therebetween.

16. In a safety razor magazine and blade assembly, the combination of: a base member having a longitudinal bridge member provided with curved surfaces at either end thereof, said base member having a first recess for a double-edged ribbon blade supply coil and a second recess to receive used portions of the blade; a spindle journaled in the first recess, said spindle carrying a transverse pin thereon; a double-edged ribbon blade adapted to be rotatably contained as a coil in the first recess, said blade having a plurality of longitudinal slots centrally thereof which are adapted to be engaged by said pin, whereby axial movement of the ribbon blade coil with respect to the spindle is restricted; means whereby the ribbon blade may be led from the first recess across the bridge and into the second recess; and a cover member for said base member, said cover member having a pair of ears transversely thereof adapted to overlie said bridge and to thus form a pair of narrow channels for said blade.

17. In a safety razor magazine and blade assembly, the combination of: a base member having a longitudinal bridge member provided with curved surfaces at either end thereof, said base

member having a first recess for a double-edged ribbon blade supply coil and a second recess to receive used portions of the blade; a spindle journaled in the first recess, said spindle carrying a transverse pin thereon; a double-edged ribbon blade adapted to be rotatably contained as a coil in the first recess, said blade having a plurality of longitudinal slots centrally thereof which are adapted to be engaged by said pin, whereby axial movement of the ribbon blade coil with respect to the spindle is restricted; means whereby the ribbon blade may be led from the first recess across the bridge and into the second recess; means on the curved surface of the bridge and adjacent said second recess whereby sidewise motion of the ribbon blade is restricted; and a cover member for said base member, said cover member having a pair of ears transversely thereof adapted to overlie said bridge and to thus form a pair of narrow channels for said blade.

18. In a safety razor magazine and blade assembly, the combination of: a base member having a longitudinal bridge member provided with curved surfaces at either end thereof, said base member having a first recess for a double-edged ribbon blade supply coil and a second recess to receive used portions of the blade; a spindle journaled in the first recess, said spindle carrying a transverse pin thereon; a double-edged ribbon blade adapted to be rotatably contained as a coil in the first recess, said blade having a plurality of longitudinal slots centrally thereof which are adapted to be engaged by said pin, whereby axial movement of the ribbon blade coil with respect to the spindle is restricted; means whereby the ribbon blade may be led from the first recess across the bridge and into the second recess; a pair of parallel shoulders on the curved surface of the bridge adjacent said second recess, said shoulders forming a groove in which the ribbon blade is carried, thus restricting sidewise motion of the blade; and a cover member for said base member, said cover member having a pair of ears transversely thereof adapted to overlie said bridge and to thus form a pair of narrow channels for said blade.

19. In a safety razor magazine and blade assembly, the combination of: a base member having a longitudinal bridge member provided with curved surfaces at either end thereof, said base member having a first recess for a double-edged ribbon blade supply coil and a second recess to receive used portions of the blade; a spindle journaled in the first recess, said spindle carrying a transverse pin thereon; a double-edged ribbon blade adapted to be rotatably contained as a coil in the first recess, said blade having a plurality of longitudinal slots centrally thereof which are adapted to be engaged by said pin, whereby axial movement of the ribbon blade coil with respect to the spindle is restricted; means whereby the ribbon blade may be led from the first recess across the bridge and into the second recess; a pair of parallel shoulders on the curved surface of the bridge adjacent said second recess, said shoulders forming a groove in which the ribbon blade is carried, thus restricting sidewise motion of the blade; and a cover member for said base member, said cover member having an ear transversely thereof adapted to overlie said bridge and to thus form a narrow channel for said blade.

20. In a safety razor magazine and blade assembly, the combination of: a base member having a longitudinal bridge member provided with

curved surfaces at either end thereof, said base member having a first recess for a double-edged ribbon blade supply coil and a second recess to receive used portions of the blade; a spindle journaled in the first recess, said spindle carrying a transverse pin thereon; a double-edged ribbon blade adapted to be rotatably contained as a coil in the first recess, said blade having a plurality of longitudinal slots centrally thereof which are adapted to be engaged by said pin, whereby axial movement of the ribbon blade coil with respect to the spindle is restricted; means whereby the ribbon blade may be led from the first recess across the bridge and into the second recess; a winding reel journaled in said second recess having means for attaching the end of said ribbon blade thereto and having means whereby the reel may be turned so that used portions of the blade may be wound thereupon; ratchet means cooperating with said winding reel so that tension may be maintained on said ribbon blade; and a cover member for said base member, said cover member having a pair of ears transversely thereof adapted to overlie said bridge and to thus form a pair of narrow channels for said blade.

21. In a safety razor, a holder for a disposable magazine member, said holder comprising: means providing a pocket for the reception of a disposable magazine member; a clamping member operably connected to said pocket-providing means, the free end of said clamping member being curved to form a spring member for engagement in a recess in said pocket-providing means; a winding knob rotatably carried on said pocket-providing means, said winding knob having a projection thereon adapted to be removably directed into said pocket; and spring means in said pocket-providing means adapted to force a magazine member against said clamping means.

22. In a safety razor, a holder for a disposable magazine member, said holder comprising: means providing a pocket for the reception of a disposable magazine member; a clamping member operably connected to said pocket-providing means, the free end of said clamping member being curved to form a spring member for engagement in a recess in said pocket-providing means; a winding knob rotatably carried on said pocket-providing means, said winding knob having a projection thereon adapted to be removably directed into said pocket; and spring means

in said pocket-providing means adapted to force a magazine member against a portion of said clamping means, whereby the magazine member may be operably contained in said holder.

5 23. In a magazine for a double-edged razor, the combination of: a base member having a bridge thereon and having a first recess therein adapted to contain a double-edged slotted ribbon blade coil and a second recess therein to receive used portions of the blade; a spindle journaled in the first recess, said spindle carrying a transverse pin thereon for engagement in a slotted blade coil; means whereby a ribbon blade may be led from the first recess across the bridge and into the second recess; and blade edge-contacting means adjacent said second recess, said last means cooperating with the pin on said spindle to maintain unused sharpened edges of the ribbon blade out of contact with the magazine.

10 24. In a magazine for a double-edged razor, the combination of: a base member having a longitudinal bridge member provided with curved surfaces at either end thereof, said base member having a first recess therein adapted to contain a double-edged slotted ribbon blade coil and a second recess therein to receive used portions of the blade; a spindle journaled in the first recess, said spindle carrying a transverse pin thereon for engagement in a slotted blade coil; means whereby a ribbon blade may be led from the first recess across the bridge and into the second recess; and a pair of parallel shoulders on the curved surface of the bridge adjacent said second recess, said shoulders forming a groove in which the ribbon blade is carried, thus restricting sidewise motion of the blade, said shoulders cooperating with the pin on said spindle to maintain correct alignment of the ribbon blade.
